UNITED STATES PATENT OFFICE.

GEORGE M. EDISON AND JOHN WHEELER, OF GRAND RAPIDS, MICHIGAN.

DESIGN FOR A HOT-AIR FURNACE.

SPECIFICATION forming part of Design No. 29,295, dated August 30, 1898.

Application filed August 2, 1898. Serial No. 687,566. Term of patent 14 years.

To all whom it may concern:

Be it known that we, GEORGE M. EDISON and JOHN WHEELER, citizens of the United States, residing at Grand Rapids, in the county 5 of Kent and State of Michigan, have invented and produced a new and original Design for Hot-Air Furnaces, of which the following is a specification, reference being had to the accompanying drawing, forming part thereof.

10 The drawing represents a perspective of a hot-air furnace, showing our new design.

As shown in the drawing, the leading or material features of our design consist in a fire-box A, having at each side parallel vertical tubes B, a rectangular box C above the fire-box and extended rearwardly beyond the same, a flat front I, having doors J J' in the middle, inclined pipes K K at each side of the doors, and a series of caps L below the 20 doors.

The fire-box A is rectangular in form and provided with a front I, considerably larger than the front of the fire-box, and in the middle thereof are the doors J J', mounted on a 25 separate plate or panel M in the front. K K are inclined pipes projecting from the said front, each pipe having an elbow at its respective ends connecting it to said front. At each side of the fire-box A is a series of parallel vertical tubes B, open at their upper 30

ends and having elbows at their lower ends connecting them with the fire-box. Above the fire-box A is a rectangular box C, extending rearwardly beyond the fire-box. Pipes D extend downwardly from the rear 35 end of the box C and thence horizontally beneath the fire-box and through the lower part of the front I and are provided with the caps L, projecting from the said front. Other pipes E' also project through the front 40 and have similar caps L and extend parallel to the pipes D' and thence upward at E each side of the box C', and thence inward and unite above said box, whence a T F extends rearward to a vertical pipe G. Another 45 pipe H extends upward from the box C' and thence rearward above the T F to the said pipe G'.

Having thus fully described our invention, what we claim as new, and desire to secure by 50 Letters Patent, is—

The design for a hot-air furnace substantially as herein shown and described.

In testimony whereof we affix our signatures in presence of two witnesses.

GEORGE M. EDISON.
JOHN WHEELER.
